UNITED STATES PATENT OFFICE.

JOSEPH S. SMITHSON, OF CHICAGO, ILLINOIS.

DRESSING HOGS.

SPECIFICATION forming part of Letters Patent No. 258,147, dated May 16, 1882.

Application filed February 23, 1882. (No model.)

To all whom it may concern:

Be it known that I, JOSEPH S. SMITHSON, a subject of the Queen of Great Britain, now residing in Chicago, in the county of Cook and State of Illinois, have invented certain new and useful Improvements in Preparing Hogs, of which the following is a specification.

My invention is an improved mode of treating hogs, whereby the removal of the hair and bristles is facilitated and the risks connected with the ordinary mode of singeing avoided.

The singeing of hogs in the ordinary manner has been attended with many objections, especially in winter, when the hair and bristles are strong and frequently matted with dirt, as the heat required to destroy them is so great that the less protected and more delicate parts of the flesh are burned and blistered, thus impairing the value of the meat.

I have found that by scalding and removing the hair, bristles, and dirt previous to singeing the latter operation is performed with greater rapidity, the bristles and hair are preserved to be used for other purposes, while the skin can be thoroughly singed without injuring any part, and the value of the meat is increased.

In carrying out my invention I first subject the animal to treatment with scalding water, then scrape to remove the bristles, as usual, then singe the carcass, and then scrape the same.

The preliminary scalding softens the outer cuticle and loosens the hair and bristles, and it is found that the subsequent heating causes this outer cuticle to become loose, so that it is readily scraped off, thereby removing all the hair and leaving a smooth, clean surface, without in the least burning the thick skin or flesh.

I claim—

The within-described mode of treating the carcass of the hog, the same consisting in first scalding the carcass with hot water and scraping off the bristles, then singeing, and then scraping to remove the hair and outer cuticle, substantially as set forth.

In testimony whereof I have signed my name to this specification in the presence of two subscribing witnesses.

JOS. S. SMITHSON.
